UNITED STATES PATENT OFFICE.

FREDERICK A. DIXON, OF OTTAWA, CANADA.

RAIL-JOINT FASTENING.

SPECIFICATION forming part of Letters Patent No. 689,388, dated December 24, 1901.

Application filed April 4, 1901. Serial No. 54,384. (No model.)

To all whom it may concern:

Be it known that I, FREDERICK AUGUSTUS DIXON, a citizen of the Dominion of Canada, residing in the city of Ottawa and Province 5 of Ontario, Canada, have invented certain new and useful Improvements in Rail-Joint Fastenings; and I do hereby declare that the following is a full, clear, and exact description of the same, reference being had to the accompanying drawings, forming a part hereof.

My invention, which will be hereinafter fully set forth and claimed, relates to boltless railroad-rail joints.

The object of my invention is a railroad-rail 15 joint combining simplicity and rapidity of adjustment with great strength of support and permanency and to obtain cheapness and lightness without sacrifice of security by freedom from complicated details and from multiplicity of parts.

Figure 1 shows my improved rail-joint in cross-section. Fig. 2 is a perspective view of the same, showing the joint complete. Fig. 3 is a similar perspective view showing one 25 rail and one joint-piece removed. Fig. 4 is a horizontal section of the same on line 4-4, Fig. 1. Fig. 5 is a reverse view of the key, and Fig. 6 is a view of the tie-plate.

A A are the rail ends to be jointed, Figs. 1, 30 2, and 3.

B B are joint-pieces, each a counterpart of the other and serving the combined purpose of fish-plates, chairs, and braces. The inner face of each joint-piece fits the rail 35 snugly, its contact-surface extending from the under side of the head at the point 2 down the web and over and around the foot to the center of the same at the point 3. The cross-section of the two joint-pieces, together with 40 the rail, form when in position a truncated pyramid having straight sides and a straight base. At the joint-line 3 the thickness of both pieces is reduced to form a fillet b, and adjoining this a groove b' is formed, the reduction being made from the top downward, and a distinct locking-shoulder b² is thus produced 45 within a recess 4 under the foot of the rail in both joint-pieces. This recess is adapted to receive a key C, having a central groove 50 c, equivalent in width to the width of the two fillets b b and so adapted that the sides of the groove engage and hold the locking-shoulders

b² b², the outer edges of the key being preferably tapered longitudinally and the cross-section of said key being adapted to fit the recess 4. When the two joint-pieces are in position on the rail and the key C is driven in the recess 4, they are held firmly together. As the key is under the foot of the rail and not readily perceptible, the key may be 60 formed with an indicator consisting of a transverse finger c', Figs. 2, 4, and 5, which is preferably bent up and will at any time indicate the actual position of the key. Near each rail end a slot a is formed in the rail-foot at 65 each side, Figs. 3 and 4. The joint-pieces have corresponding lugs b³ to engage said slots and prevent endwise separation of the rails, due allowance being made for expansion and contraction of the latter. The joint-pieces 70 are placed on a tie-plate D, provided with spike-holes d, registering-notches and countersinks b⁴ being formed in the joint-pieces to receive the spikes, securing them to the tie E. At one end of the tie-plate an upwardly-projecting lug d' is formed, against which the head of the key abuts.

It will be observed that apart from the tie-plate, which is common to railway-joints, my improved joint consists of only three pieces 80 and no bolts are required. After the rails have been placed in position end to end the two joint-pieces are brought in contact with the rails, the key inserted and driven in, the tie-plate placed under and the tie brought 85 up, and the joint is complete after being spiked. To replace a rail, it is simply necessary to extract the spikes, remove the tie-plate, and withdraw the key, which for this purpose is made a little longer than the joint-pieces, when one or both of the joint-pieces 90 may be removed, the rail removed, the new one placed in position, and the parts readjusted, as before.

I claim as my invention—

1. In a key-rail-joint fastening, the combination with the rail ends of a pair of joint-pieces counterparts of each other and in contact with the rails and having along their meeting edge a recess with locking-shoulders, 100 a key fitting said recess and having a groove forming locking-shoulders, a device for the prevention of the separation of the rails lengthwise by slots in the rail-base near the

rail ends and registering-lugs in the joint-pieces, a device indicating the position of the key in the fastening and a device for preventing the working loose of the key, substantially as set forth.

5. 2. In a key-rail-joint fastening, the combination with a pair of rail ends of two joint-pieces in snug contact with the web and foot of the rail and forming with the latter a cross-section of pyramidal outline, a pair of locking-shoulders formed in a recess along the joint at the bottom and a grooved key with locking-shoulders fitting said recess and engaging the locking-shoulders of the joint-pieces, substantially as set forth.

10. 3. In a key-rail-joint fastening, the combination with the rails of a pair of joint-pieces counterparts of each other fitting the rail snugly on web and foot and having a flat base with a joint in the center and a recess with locking-shoulders along the edges of the joints, a grooved key entering said recess and engaging said shoulders, a slot near each rail end at each side in the foot and a registering-lug for each slot in the joint-pieces, substantially as set forth.

15. 4. In a key-rail-joint fastening, the combination with the rails of a pair of joint-pieces

counterparts of each other fitting the rail snugly on web and foot and having a flat base 30 with a joint in the center below the rail-foot, a locking-shoulder formed by a groove in a recess along the joint in each joint-piece, and a grooved and tapered key entering said recess and engaging said locking-shoulders, substantially as set forth.

5. 5. In a key-rail-joint fastening, the combination with the rails of a pair of joint-pieces counterparts of each other fitting the rails snugly on web and foot and having a flat base 40 with a joint in the center below the rail-foot, the edges of said joint being recessed from above and formed with locking-shoulders, a grooved and tapered key fitting said recess and engaging the locking-shoulders, a tie-plate supporting the joint-pieces and a lug on said tie-plate against which the head of the key abuts when the joint is locked, substantially as set forth.

20. In testimony whereof I have signed my 50 name to this specification in the presence of two subscribing witnesses.

FREDERICK A. DIXON.
